UNITED STATES PATENT OFFICE.

MANUEL LASSEN, OF DETROIT, MICHIGAN.

PRESSURE-CONTROLLED SWITCH.

Application filed October 17, 1924. Serial No. 744,285.

This invention relates to means for opening and closing electric circuits as the pressure of fluid increases above or decreases below predetermined points, and its object is to provide a device of this character which can be adjusted as to pressure, which shall not readily get out of order, and which can be produced at relatively low cost.

This invention comprises a fluid-pressure operated diaphragm and a lever actuated thereby in one direction and resilient means to move the lever in the opposite direction, a pivoted closed tube into which two contacts extend and in which a globule of mercury is adapted to flow into one end to close the circuit between such contacts when the tube is tilted into one position and is adapted to flow into the other end to break the circuit between said contacts when the tube is tilted into its other position, and a deferred-movement connection between said lever and said tube.

It further consists in means for varying the tension of the resilient means so as to predetermine the pressure of the fluid at which the electric circuit between said contacts shall be opened.

It also consists in the details of construction illustrated in the accompanying drawings and particularly pointed out in the claims.

In the drawing, Fig. 1 is an elevation of my improved switch with the end of the cover broken away. Figs. 2 and 3 are sections on the lines 2-2 and 3-3 of Fig. 1, respectively. Fig. 4 is a view similar to Fig. 1 with the switch tube removed. Fig. 5 is an elevation of the multiplying lever.

Similar reference characters refer to like parts throughout the several views.

The base 1 is preferably circular and has a hub 2 to receive the pipe 3 and a hole 4 leading to the space adjacent the diaphragm 5 which is of any desirable metal, depending upon the character of the fluid under pressure which is to control the switch. A packing ring 6 of fabric or composition prevents leakage between the diaphragm and the base and the diaphragm is held in position by the metallic washer 7, by the disk 8 and by the screws 9. The disk 8 has a central aperture 10 through which the button 12 extends, this button preferably having a

circular foot 13 contacting with the diaphragm and attached thereto if desired. 55

A small bracket 14 is attached to the disk 8 and supports the pivot pin 15 on which the main operating lever 16 is mounted. This lever carries an adjustable screw 17 which contacts with the button 12 and a 60 second screw 18 which contacts with the disk 8. Two threaded posts 19 extend from the disk 8 through the cross bar 20 which presses the main lever 16 toward the disk 8, through the springs 22 which engage this 65 cross bar and the nuts 23, and through holes in the cap 24 which is held in place by the nuts 25. The nuts 23 and springs 22 determine the pressure of the fluid below the diaphragm which is able to swing the main 70 lever 16 against the tension of these springs. Washers 26 may be employed if desired.

A small bracket 27 secured to the disk 8 carries a pin 28 on which the multiplying lever 29 is mounted, this lever having a 75 notch to receive the pin 30 extending laterally from the main lever 16. A link 32 hooks into the outer end of the multiplying lever and extends to the switch, but its connection therewith will be explained later on. 80

The cap 24 has two notches to receive the sleeves 33 which support the conductors 34 and 35 and the flexible wires 36 and 37 connecting to these conductors. The wires 36 and 37 connect into the well known switch 85 tube 38 to the bars 39 and 40 which terminate in the contacts 41 and 42. Within the tube is a globule 43 of mercury which is adapted to close the circuit between the contacts 41 and 42. 90

Two posts 44 extend from the disk 8 and carry the short plates 45, which, in turn, support the pivot pins 46. A small yoke 47 is mounted to hang on these pins and a resilient plate 48 attached to the bottom of 95 this yoke has a curved arm 49 which fits around the tube 38 and supports it. The tube therefore tilts on the axis of the pins 46 and this axis is preferably about the middle point of the tube. 100

Mounted on these pins is a larger yoke having sides 50 and a top 51. Attached to the lower end of the front side of this yoke is a short arm 52 (Fig. 4) to which the link 32 connects. This large yoke will therefore swing to the right (Figs. 1 and 4) 105

when the springs 22 overcome the pressure of the fluid on the diaphragm 5 and to the left when the pressure of the fluid on the diaphragm overcomes the springs. A tension spring 53 connects the middle point of the top 51 of the large yoke with the center of the middle portion of the yoke 47.

When the pressure of the fluid back of the diaphragm is below the predetermined point, the parts are in the positions shown in the drawing. As this pressure increases sufficiently, the operating lever 16 swings away from the disk 8 and the multiplying lever 29 swings down (in Figs. 1 and 4) causing the arm 52 (Fig. 4) to also swing down. The upper yoke 50-51 now swings toward the left, but the lower yoke 47 remains in the position shown until the central line of the spring 53 passes to the left 20 of the axis of the pivot pins 46, at which time the spring 53 suddenly swings the lower yoke clockwise, or to the left in Figs. 1 and 4, swinging the tube 38 to such an extent as to cause the globule 43 to run to the right end 25 thereof and bridge the contacts 41 and 42. This delayed-action, quick-operating device reduces arcing at the contacts 41 and 42.

It is evident that this tube might be reversed and the circuit between the contacts broken by increasing pressure of the controlling fluid and made with decreasing pressure. However, the yoke 50-51 will swing to the right or clockwise with decreasing pressure. The yoke 50-51 may swing considerable distances either way without affecting the yoke 47 and the switch tube and the electric circuit will not be affected by small variations of pressure. I prefer to attach a stop plate 60 with arms 61 to the cross bar 20 to limit the movements of the upper yoke and to attach a stop plate 62 with arms 63 to the posts 44 to limit the movements of the lower yoke and switch tube.

The details of construction and the proportions of the parts may all be changed by those skilled in the arts without departing from the spirit of my invention as set forth in the following claims.

I claim:

50 1. In a pressure controlled electric switch, the combination of a base and a pressure controlled diaphragm mounted thereon, a main lever moved in one direction by the diaphragm, resilient means to move the lever in the opposite direction, a multiplying lever, a pivoted switch tube and contacts and a globule of mercury therein, and resilient connections between the multiplying lever and said tube to swing the same on its pivot as the pressure on the diaphragm increases and decreases.

2. In a pressure controlled electric switch, the combination of a base and a pressure controlled diaphragm mounted thereon, a main lever moved in one direction by the dia-

phragm, resilient means to move the lever in the opposite direction, a multiplying lever, a pivoted switch tube and contacts and a globule of mercury therein, and connections between the multiplying lever and said tube to swing the same on its pivot as the pressure on the diaphragm increases and decreases comprising a pair of yokes, one connected to the multiplying lever and the other to the switch tube, and a spring connecting said yokes.

3. In a pressure controlled electric switch, the combination of a base and a pressure controlled diaphragm mounted thereon, a main lever moved in one direction by the diaphragm, resilient means to move the lever in the opposite direction, a multiplying lever, a pivoted switch tube and contacts and a globule of mercury therein, and connections between the multiplying lever and said tube to swing the same on its pivot as the pressure on the diaphragm increases and decreases, said resilient means being adjustable as to tension so as to predetermine the pressure on the diaphragm at which the switch tube will be swung.

4. In a pressure controlled electric switch, the combination of a base, a disk, a diaphragm between them, washers spacing the diaphragm from the disk and base, a button on the diaphragm extending through a hole in the disk, a main lever pivoted on the disk and movable in one direction by said diaphragm, springs mounted on the disk to resist the movement of the lever, a switch tube pivotally mounted on the disk, a movement multiplying device operated by the main lever, and means connecting said multiplying device to said switch tube.

5. In a pressure controlled electric switch, the combination of a base, a disk, a diaphragm between them, washers spacing the diaphragm from the disk and base, a button on the diaphragm extending through a hole in the disk, a main lever pivoted on the disk and movable in one direction by said diaphragm, springs mounted on the disk to resist the movement of the lever, a switch tube pivotally mounted on the disk, a movement multiplying device operated by the main lever, and means connecting said multiplying device to said switch tube, comprising a delayed-action quick-operating mechanism to reduce arcing within said switch tube.

6. In a pressure controlled electric switch, the combination of a base, a disk, a diaphragm between them, washers spacing the diaphragm from the disk and base, a button on the diaphragm extending through a hole in the disk, a main lever pivoted on the disk and movable in one direction by said diaphragm, springs mounted on the disk to resist the movement of the lever, a switch tube pivotally mounted on the disk, a move-

ment multiplying device operated by the main lever, means connecting said multiplying device to said switch tube, and means to limit the swinging movements of said switch tube on its pivots.

7. In a pressure controlled electric switch, the combination of a base and a pressure controlled diaphragm mounted thereon, a main lever moved in one direction by the 10 diaphragm, resilient means to move the lever in the opposite direction, a multiplying lever, a pivoted switch tube and contacts and a globule of mercury therein, and connections between the multiplying lever and said tube to swing the same on its pivot as the pressure on the diaphragm increases and decreases comprising a pair of yokes, one connected to the multiplying lever and the other to the switch tube, and a spring 15 connecting said yokes, said yokes being mounted on the same pivots and the switch tube being carried by one of said yokes.

8. In a pressure controlled electric switch, the combination of a base and a pressure controlled diaphragm mounted thereon, a main lever moved in one direction by the 20 diaphragm, resilient means to move the lever in the opposite direction, a multiplying lever, a pivoted switch tube and contacts and a globule of mercury therein, connections between the multiplying lever and said 25 tube to swing the same on its pivot as the pressure on the diaphragm increases and

decreases comprising a pair of yokes pivoted to swing on a common axis, one of 35 said yokes being connected to the multiplying lever and the other to the switch tube, a spring connecting the free ends of said yokes and adapted to be carried across said axis by the yoke connected to the multiplying lever, and means to limit the movements 40 of said yokes.

9. In a pressure controlled electric switch, the combination of a base, a disk, a diaphragm between them, washers spacing the 45 diaphragm from the disk and base, a button on the diaphragm extending through a hole in the disk, a main lever pivoted on the disk and movable in one direction by said diaphragm, springs mounted on the disk to 50 resist the movement of the lever, a switch tube pivotally mounted on the disk, a movement multiplying device operated by the main lever, means connecting said multiplying device to said switch tube, an adjustable 55 screw carried by the main lever and contacting with said button, a second screw carried by the main lever and adapted to contact with the disk to limit the movement of the main lever under the force of said 60 springs, and means to adjust the tension of said springs and thereby predetermine the pressure on the diaphragm at which the switch tube shall be swung on its axis.

MANUEL LASSEN.
